OZONIZING TUBE

Bruno Lattuada, Zurich, Switzerland, assignor to Intertrade Aktiengesellschaft, Zurich, Switzerland

Application May 21, 1956, Serial No. 586,217

Claims priority, application Switzerland June 8, 1955

3 Claims. (Cl. 204—320)

This invention concerns an ozonizing tube having a holding and current supply device. As generally known, such tubes are used in air conditioning systems and have a glass cylinder which on both sides, inwardly and outwardly, is provided with a conductive layer.

It is an object of the invention to provide an ozonizing tube, having a glass cylinder supported at either end on two metal holders provided with terminals and including a portion formed as a resilient clamp for connection to a current supply releasably engaging the marginal sections, free from said layer of the glass cylinder, while at each of said marginal sections a contact strip extends from said resilient clamp to the border of the glass cylinder, one of said strips being connected to the inner conductive layer of the glass cylinder and the other to the outer conductive layer thereof.

In this manner a particularly simple holding and current supply device is provided, since these holders each are formed of a single piece and at the same time represent a portion of the current supply member.

The invention will now be more particularly described by way of example with reference to the accompanying drawing, showing an axial section through an ozonizing tube according to the invention.

Referring to the drawing, the numeral 1 designates the glass cylinder of the tube, which in a manner known per se is provided with an inner metal layer 2 and an outer metal layer 3, e.g. a thin wire meshing or perforated sheet metal. The two metal layers do not extend to the ends of the glass cylinder 1. Two metal holders 4, each consisting of a single integral piece, are provided as a support and holding means 4 for the tube. The holders 4 are secured to the bottom of the apparatus into which the tube is mounted; moreover, said holders are provided with terminals 5 for connection to a current supply.

The top end portion of the holder 4 is formed as a loop-shaped resilient clamp 4a. These clamps 4a engage the associated marginal section of the cylinder, which is free from any metal layer. Contact strips 6 and 7, respectively, formed for instance by metal foil, are engaged between each of said clamps and the adjacent end portion of the metal cylinder. The contact strip 6, disposed on the left in the drawing, is electrically connected to the outer layer 3 of the cylinder, while the contact strip 7 disposed on the right in the drawing, is electrically connected to the inner layer 2 of the cylinder. Consequently, the current supply means, extending from the terminals 5 to the two conductive layers 2, 3, are formed, each by one of the holders 4 and the associated contact strip 6 and 7, respectively.

For the removal of the tube from the described holding and current supply device, the free ends 8 of the resiliently formed clamps 4a are outwardly urged by hand, so

2

that the clamps 4a will open and the tube may be removed from the holders 4. Thereby the electric connection between the terminals 5 and the conductive layers 2 and 3 of the tube are interrupted, and a separate loosening of electrical connections thus is not required.

The described holding and current supply device consists of few individual parts which are simple in their construction; thus a simple mounting or exchanging of the tube is obtained.

10 I claim:

1. An ozonizing tube having holding and current supply means, said tube comprising a cylinder of non-conductive material open at its opposite ends, said cylinder being provided with inner and outer layers of conductive material, both ends of said cylinder having a circumferential portion free of conductive layer material, a tube supporting metal holder positioned at each end of said cylinder out of encircling engagement therewith, said holders each having a portion defining a resilient clamp for releasably receiving a portion of the wall thickness of said cylinder at the open ends thereof to resiliently support it in an axial as well as in a radial direction, said holders each having a current supply terminal thereon, and contact strips engaged between each clamp and the corresponding end portion of said cylinder, one strip providing an electrical connection between one clamp and the inner conductive layer, and another strip providing an electrical connection between the second clamp and the outer conductive layer.
- 20 2. An ozonizing tube as claimed in claim 1, wherein said holders are formed by a strip of metal forming a looped portion for engagement of the edge of said cylinder, and a free end portion extending from said looped portion and adapted to be gripped for opening the loop and removing the cylinder.
- 30 3. An ozonizing tube having holding and current supply means, said tube comprising a cylinder of non-conductive material open at its opposite ends, said cylinder being provided with inner and outer layers of conductive material, both ends of said cylinder having a circumferential portion free of conductive layer material, a tube supporting metal holder positioned at each end of said cylinder; each of said holders having a bowed portion for releasably receiving a portion of the wall of said cylinder, a current supply terminal on said holder, and contact strips engaged between each clamp and the corresponding end portion of said cylinder, one strip providing an electrical connection between one clamp and the inner conductive layer, and another strip providing an electrical connection between the second clamp and the outer conductive layer.
- 40 4. An ozonizing tube having holding and current supply means, said tube comprising a cylinder of non-conductive material open at its opposite ends, said cylinder being provided with inner and outer layers of conductive material, both ends of said cylinder having a circumferential portion free of conductive layer material, a tube supporting metal holder positioned at each end of said cylinder; each of said holders having a bowed portion for releasably receiving a portion of the wall of said cylinder, a current supply terminal on said holder, and contact strips engaged between each clamp and the corresponding end portion of said cylinder, one strip providing an electrical connection between one clamp and the inner conductive layer, and another strip providing an electrical connection between the second clamp and the outer conductive layer.
- 50 5. An ozonizing tube having holding and current supply means, said tube comprising a cylinder of non-conductive material open at its opposite ends, said cylinder being provided with inner and outer layers of conductive material, both ends of said cylinder having a circumferential portion free of conductive layer material, a tube supporting metal holder positioned at each end of said cylinder; each of said holders having a bowed portion for releasably receiving a portion of the wall of said cylinder, a current supply terminal on said holder, and contact strips engaged between each clamp and the corresponding end portion of said cylinder, one strip providing an electrical connection between one clamp and the inner conductive layer, and another strip providing an electrical connection between the second clamp and the outer conductive layer.
